Gamenote Rotating Art Supply Organizer, 191 ratings, Part No. SO1, ASIN: B08RRWP81Z, online on Amazon.com, Date First Available: Dec. 31, 2020.*

Primary Examiner — Elizabeth A. Albert

(57)

CLAIM

The ornamental design for a supply organizer, as shown and described.

DESCRIPTION

FIG. 1 is a front and top perspective view of a supply organizer, showing our new design;
FIG. 2 is a top plan view thereof;
FIG. 3 is a left side elevation view thereof;
FIG. 4 is a front elevation view thereof;
FIG. 5 is a right side elevation view thereof;
FIG. 6 is a rear elevation view thereof; and,
FIG. 7 is a bottom plan view thereof.
The broken lines in the figures illustrate portions of the article that form no part of the claimed design.

1 Claim, 7 Drawing Sheets
